UNITED STATES PATENT OFFICE.

BENJAMIN P. MCKINLEY, OF FLUSHING, NEW YORK, ASSIGNOR TO HEMCO ELECTRIC MANUFACTURING COMPANY, INC., OF LONG ISLAND CITY, NEW YORK, A CORPORATION OF NEW YORK.

PLUG CONNECTER.

Application filed December 8, 1923. Serial No. 679,293.

My invention relates to improvements in plug connectors and has for its general object the production of a new and improved plug connector which lends itself more readily to economy in manufacture and is efficient and durable when in use.

In plug connectors as heretofore made, the lightness of the parts employed made them liable to bend so as to produce short circuits during the process of manufacture and furthermore the bending is liable to result in breakage so that the per cent of "rejects" was so large as to materially reduce, if not eliminate, the profit. My improved connector has, among other objects and advantages, the reduction of rejects through such causes and further permits of more expeditious manufacture and a generally superior product. One of the prominent objects and features of my construction is an insert having a swivel connection between the internally threaded shells and a support therefor. Another object and advantageous feature of my construction is a swivel connection between the shell support and the central contact. Another object and advantageous feature of my construction is the manner of holding the externally threaded shell to the washer or plug within the same. Another object and advantageous feature of my construction is the electrical connection of the internal contacts, which co-operate with the internally threaded shell, with the externally threaded shell and the electrical connection of the internally threaded shell with the contact centrally located within the externally threaded shell.

The following is a description of an embodiment of my invention, reference being had to the accompanying drawings, in which,

Figure 1 represents a plan view of a plug connector embodying my invention;

Fig. 2 shows the same, partly in section and partly in side elevation;

Fig. 3 shows the insert for my plug connector, partly in section and partly in side elevation;

Fig. 4 shows a detail section on the line 4-4, Fig. 3;

Fig. 5 is a detail view of the frame support for the internally threaded shell;

Fig. 6 is a spring terminal for the central

contacts co-operating with the internally threaded shells;

Fig. 7 is a side elevation of one of the portions of the mold used in manufacturing my plug connector, the frame of the mold being removed;

Fig. 8 is a plan of the mold with the upper inner portion shown removed; and

Fig. 9 is a vertical section of the mold assembled with an insert therein on the line 9-9, Fig. 8.

Referring more particularly to the drawings, 2 is a central contact member having a head 4. The contact member 2 passes through a hole in a washer 6 against the outer face of which the contact head 4 of the member bears. This washer is preferably somewhat elongated as shown in Figs. 2 and 3. It is surrounded by an externally threaded plug shell 8 which has a flange 9 which engages the outer end of the washer 6 near its periphery. To the inner surface of the plug shell 8 are secured two conductors 10, the upper ends of these conductors being secured adjacent to the lower ends of the plug shell 8 by solder 12. The solder bears against a lower face upon the washer 6 and the upper ends of the conductors 10 also preferably bear against this face. The washer 6 is preferably extended the full length of the shell 8, recesses being formed therein as indicated at 14, Fig. 4, for the entrance of the ends of the conductors 10 and into which the solder is run. The engagement of the solder and ends of the conductors 10 with the opposing faces of the washer 6 hold this washer in engagement with the flange 9. The head 4 of the contact member 2 is held in engagement with the upper surface of the washer 6 by swaging out portions of the contact member 2, as at 16, a metallic washer 17 being preferably interposed.

Upon the lower end of the contact member 2 is mounted a frame 18, the contact member 2 being headed over as at 20 so as to hold the frame thereon. The head 20 is preferably so located as to permit a longitudinal movement of the frame 18 upon the contact 2 and the contact 2 may be provided with a shoulder 22 for limiting the upward movement of the frame. The frame 18 is preferably swiveled so as to be free to turn upon the contact member 2. The frame 18 is pro-

vided at its two ends with circular openings 24. 26 are two internally threaded receptacle shells adapted to receive the screw terminals of ordinary incandescent lamps. 5 These shells are provided with necks 28 which pass through the openings 24 of the frame and are then turned over so as to produce flanges 30 which hold the shells 26 in place, the construction being such as to permit the shells 26 to be turned about their axes relative to the frame 18, resulting in a swiveled connection. The contact member 2 and conductors 10 are quite massive so as to possess sufficient rigidity to withstand 15 the great pressure which is employed in molding the mass of plastic insulation about the insert and so that they are not liable to be displaced or to be bent sufficiently to come into contact with one another and 20 thus produce a short circuit. 32 is a mass of insulation which is molded while plastic about the lower portion of the insert so that it extends to the bottom of the washer 6 and surrounds the lower portions of the contact 25 member 2 and conductors 10 and shells 26, as shown in Fig. 2. The shells 26 are thus embedded in the insulation and all the parts are rigidly held together. After the mass of insulation is molded about the insert, a 30 spring contact 34 is applied to the inner end of each of the conductors 10. This contact when first applied has two end portions bent at a right angle, as shown in dotted lines, one of which is perforated at 36. The perforation 36 is placed over the corresponding conductor 10 and the end of the conductor is preened down so as to hold the contact in position. The free end of the contact is then bent down to the position shown in 40 Fig. 2, thus affording a spring contact. The preened end of the conductor 10 acts as a stop so that the contact can not be bent down below its limit of elasticity.

In applying the mass of insulation to the 45 insert above referred to, a multi-part mold is used consisting of a base portion, which for convenience is made up of a plate 38 to which is secured a frame 40. Within this frame is a fixed inner member 42 which is also secured to the plate 38 and fills the 50 lower part of the frame with the exception of the three rectangular portions 44 and 46. The upper face of this inner member has recesses conforming to one-half of the exterior of the desired molded mass. A similar inner portion 48 is secured to a plate 55 50 and is removable therewith.

The mold also comprises a block 52 filling the recess 46 and provided with a boss 54 60 which is surrounded by the members 42 and 48 and is provided with a recess 56 which fits over the externally screw-threaded shell 8 so as to slide thereon. The mold also comprises two blocks 58 which fill the recesses 44 and which are each provided with

a projection 60 which extends between the members 42 and 48, said member being screw-threaded on its inner end so as to engage the internal screw-threads of the shells 26. These projections 60 are provided with 70 recesses 62 into which the ends of the conductors 10 extend respectively and also provided with extensions 64 which result in forming cavities 63 in the mass of insulation in which portions of the spring terminals 34 75 are located.

In using the mold the blocks 60 are first screw-threaded into the receptacle shells 26 and the block 52 is then applied as shown in Fig. 9. The insert, together with the blocks 52 and 58 thus applied, are inserted within the frame 40 of the mold as shown in Fig. 9, the swiveling of the shells 26 permitting the shells to be turned with the blocks 58 so that the blocks are in proper 85 alignment for insertion. The recesses 62 hold the conductors 10 in the proper central relation with respect to the shells 26. After the blocks, together with the insert, have been introduced into the mold, the upper 90 member 48 is put in position, the same being guided by the edges of the cavity 66 in the frame of the mold, a proper amount of insulating material, heated to render it 95 plastic, having been first introduced. Pressure is then applied to the top plate 50 so as to cause the insulating material to flow into all the empty spaces and embed the parts with which it comes in contact. In practice the pressure applied is a very high 100 pressure which insures this result.

The movable parts of the mold are then removed by means of an extractor forced within the openings 68 and the resulting product allowed to cool. After cooling, the 105 terminals 34 are applied, the ends of the conductor 10 being preened down and the terminals 34 bent to the position shown in Figs. 2 and 6.

The swiveling of the frame 18 upon the 110 contact member 2 permits the proper positioning of the ends of the conductors 10 for enabling the plugs 60 to be screwed home within the shells 26 and the subsequent positioning of the blocks 58 for insertion in the 115 mold. The capacity for longitudinal movement between the frame 26 and the contact member 2 permits of slight variations in manufacturing those several parts. The connection between the frame 18 and the 120 contact member 22 is a fairly tight connection, with the result that there is a proper electrical connection between them and the same is true of the connection between the shells 26 and the frame 18.

With the plug connector thus constructed, the process of manufacture is simple and accurate, furnishing a uniform product with practically no danger of imperfections.

As will be evident to those skilled in the 130

art, my invention permits of various modifications without departing from the spirit of the invention and the scope of the appended claims.

5. What I claim is:

1. In a plug connector, the combination of an externally screw-threaded plug shell, an insulating washer within the same, a contact member passing through said washer, 10 two internally threaded receptacle shells electrically connected to said contact member, two contacts connected to said externally threaded plug shell and having their ends centrally located within said internally threaded receptacle shells respectively, and a mass of insulating material molded about said internally threaded receptacle shells and extending to said washer, said externally threaded plug shell being internally flanged 15 at its outer end and having solder secured to its inner surface adjacent to its other end holding said washer against said flange.
2. In a plug connector, the combination of an externally screw-threaded plug shell, 20 an insulating washer within the same, a contact member passing through said washer, two internally threaded receptacle shells electrically connected to said contact member, two contacts connected to said externally threaded plug shell and having their ends centrally located within said internally threaded receptacle shells respectively, and a mass of insulating material molded about 25 said internally threaded receptacle shells and extending to said washer, said externally threaded plug shell being internally flanged at its outer end and having solder secured to its inner surface adjacent to its other end holding said washer against said flange, said 30 washer having peripheral recesses extending from its inner end and said two contacts having portions extending into said recesses and secured by said solder.
3. In a plug connector, the combination of an externally threaded plug shell, a contact member passing through said shell and insulated therefrom, a frame connected to the lower end of said contact member, two internally threaded receptacle shells swiveled 35 to said frame, and insulation in which said internally threaded receptacle shells are embedded and securing the same rigidly to said externally threaded plug shell and to said frame.
4. In a plug connector, the combination of an externally threaded plug shell, a contact member passing through said shell and insulated therefrom, a frame loosely connected to the lower end of said contact member, 40 two internally threaded receptacle shells swiveled to said frame, and insulation in which said internally threaded receptacle shells are embedded and securing the same

rigidly to said externally threaded plug shell, said internally threaded receptacle shells 65 being swiveled to and free to turn axially in said frame before said insulation is applied and held from movement by said insulation.

5. In a plug connector a plug having a 70 plug shell contact and a central contact, a frame electrically connected to one of said contacts and having a plurality of openings therein, a plurality of internally threaded receptacle shells each having one end within 75 one of said openings, respectively, and swivelled to said frame and a unitary mass of molded material surrounding said frame and internally threaded receptacle shells and holding said receptacle shells from movement relatively to said frame.

6. In a plug connector a plug having a 80 plug shell contact and a central contact, a frame electrically connected to one of said contacts and having two openings therein, 85 two internally threaded receptacle shells each having one end within one of said openings, respectively, and swivelled to said frame, and a mass of molded insulating material surrounding said frame and internally 90 threaded receptacle shells and holding said receptacle shells from movement relatively to said frame, and central contacts within said receptacle shells connected to the other contact of said plug.

7. In a plug connector the combination of an externally threaded plug shell, a contact member passing through said shell and insulated therefrom, a frame having a swiveled connection to the lower end of said contact member permitting a longitudinal movement of the frame relatively to said contact independent of the rotary movement permitted by said swiveled connection, two internally 100 threaded receptacle shells secured to 105 said frame, and insulation in which said receptacle shells are embedded and holding said frame from movement relatively to said contact member.

8. In a plug connector the combination of an externally threaded plug shell, a contact member passing through said shell and insulated therefrom, a frame having a swiveled connection to the lower end of said contact member permitting a longitudinal movement of the frame relatively to said contact independent of the rotary movement permitted by said swiveled connection, two internally 110 threaded receptacle shells swiveled to said frame, and insulation in which said receptacle shells are embedded, securing the same rigidly to said plug shell and holding said frame from movement relatively to said contact member.

BENJAMIN P. MCKINLEY.
